CLAIM

The ornamental design for garment hanger with notch, as shown and described.

DESCRIPTION

FIG. 1 is a front elevation view of a garment hanger with notch showing our new design, the rear elevation view being a mirror image thereof;

FIG. 2 is a left side elevation view thereof, the right side elevation view being a mirror image thereof;

FIG. 3 is a top view thereof; and,

FIG. 4 is a bottom view thereof.

The subject matter shown in broken lines is for illustrative purposes only and forms no part of the claimed design.
